(57) **ABSTRACT**

A new and distinct *Lagerstroemia* cultivar named 'SMNLIDS' is disclosed, characterized by intense pink flower color, and dark green with a silver sheen and bronze foliage. Plants are dwarf, compact and well-branched. The new variety is a *Lagerstroemia*, normally used for outdoor ornamental purposes.

3 Drawing Sheets

1

Latin name of the genus and species: *Lagerstroemia indica*.

Variety denomination: 'SMNLIDS'.

BACKGROUND OF THE INVENTION

The new *Lagerstroemia* cultivar is a product of a planned breeding program conducted by the inventor, Megan Mathey, in Grand Haven, Mich. The objective of the breeding program was to develop new colors in leaves and flowers. The open pollination resulting in this new variety was made during July of 2013.

The seed parent is the commercial variety referred to as *Lagerstroemia* 'Coral Magic', U.S. Plant Pat. No. 23,922. The pollen parent is unidentified. The new variety was selected in July of 2015 by the inventor in a group of seedlings resulting from the 2013 open pollination, in a commercial nursery in Grand Haven, Mich.

Asexual reproduction of the new cultivar has been performed by softwood cuttings. This was first performed at the same nursery in Grand Haven, Mich. during July of 2015, and has shown that the unique features of this cultivar are stable and reproduced true to type in multiple successive generations.

SUMMARY OF THE INVENTION

The cultivar 'SMNLIDS' has not been observed under all possible environmental conditions. The phenotype may vary somewhat with variations in environment such as temperature, day length, and light intensity, without, however, any variance in genotype.

The following traits have been repeatedly observed and are determined to be the unique characteristics of 'SMNLIDS'. These characteristics in combination distinguish 'SMNLIDS' as a new and distinct *Lagerstroemia* cultivar:

1. Dark green foliage with a silver sheen, bronze new growth.
2. Well-branched plants.

2

3. Intense pink flower color.
4. Dwarf plant.

PARENT COMPARISON

Plants of the new cultivar 'SMNLIDS' are similar to plants of the seed parent, in most horticultural characteristics; however, plants of the new cultivar 'SMNLIDS' differ in the following;

1. The new variety has dark green leaves with a silver sheen, while the seed parent has green leaves.
2. The new variety has darker pink flowers, while the seed parent has lighter pink flowers.

COMMERCIAL COMPARISON

Plants of the new cultivar 'SMNLIDS' are comparable to the commercial variety *Lagerstroemia* 'G2X133271', U.S. Plant Pat. No. 27,474. The two *Lagerstroemia* varieties are similar in most horticultural characteristics; however, the new variety 'SMNLIDS' differs in the following;

1. The new variety is a dwarf; this comparator is a larger plant.
2. Foliage of the new variety has hues of silver, burgundy and green; comparator has green foliage.
3. New variety has hot pink flowers; comparator has darker red-pink flowers.

BRIEF DESCRIPTION OF THE PHOTOGRAPHS

The accompanying photograph in FIG. 1 illustrates in full color a typical plant of 'SMNLIDS' in a 3 gallon pot. Age of the plant photographed is approximately 1.5 to 2 years old from a rooted cutting.

FIG. 2 illustrates a flowering plant outdoors at approximately 3 years old in Grand Haven, Mich.

FIG. 3 illustrates a close up of the foliage.

The photographs were taken using conventional techniques and although colors may appear different from actual

colors due to light reflectance it is as accurate as possible by conventional photographic techniques.

DETAILED BOTANICAL DESCRIPTION

In the following description, color references are made to The Royal Horticultural Society Colour Chart 2015 except where general terms of ordinary dictionary significance are used. The following observations and measurements describe 'SMNLIDS' plants grown in a poly house during August 2017, in Grand Haven, Mich. The growing temperature ranged from approximately 18° C. to 27° C. during the day and from approximately 5° C. to 10° C. during the night. General light conditions are normal sunlight and numerical values represent averages of typical plant types.

Botanical classification: *Lagerstroemia indica* 'SMNLIDS'.

PROPAGATION

Type of propagation typically used: Softwood cuttings.

Time to initiate roots: 21 days at 18-27° C.

Time to produce a rooted cutting: 1-2 months at 18-27° C.

Root description: Thin, dense, fibrous, moderate branching.

White in color, not accurately measured with R.H.S. Chart.

PLANT

Age of plant described: 2-3 years old from a rooted cutting.

Container size: 3 gallon container.

Overall plant shape: Compact, rounded.

Growth habit: Freely branching outward. Deciduous flowering shrub.

Plant spread: 64 cm.

Plant height: 52 cm.

Plant vigor: Good.

Branching habit: Basal.

Length of primary lateral branches: 33 cm.

Diameter of lateral branches: 4 mm.

Quantity of lateral branches: 26.

Stem:

Color.—New growth: RHS Greyed-Green 193C, flushed Greyed-Red 179A. Newest branches Greyed-Red 179A. Old growth: RHS Greyed-Brown 199C.

Shape.—New growth: Square. Old growth: Round.

Strength.—Good.

Aspect angle.—15-80°.

Texture.—New growth slightly pubescent, old growth woody.

Internode length: 1.5 cm.

FOLIAGE

Leaf:

Arrangement.—Sub-opposite.

Average length.—4.5 cm.

Average width.—2 cm.

Shape of blade.—Lanceolate.

Apex.—Acute.

Base.—Obtuse.

Margin.—Entire.

Texture of top surface.—Smooth, waxy.

Texture of bottom surface.—Smooth, slightly ribbed.

Color.—Young foliage upper side: Mix of RHS Greyed-Purple 187A and Green 143A. Young foliage

under side: RHS Green 146C. Mature foliage upper side: RHS Yellow-Green 147A. Sheen Greyed-Purple N187D. Mature foliage under side: RHS Yellow-Green 147B.

Venation.—Type: Pinnate. Venation color upper side: RHS Greyed-Red 179B. Venation color under side: RHS Greyed-Red 181C.

Petiole.—Length: 1 mm. Diameter: 1.5 mm. Texture, upper side: Smooth. Texture, under side: Smooth. Color, upper side: RHS Greyed-Purple N186A. Color, under side: RHS Greyed-Purple N186A.

FLOWER

15 Natural flowering season: Late Summer to October.

Inflorescence form: Panicle at terminal ends.

Flowers per inflorescence: Average 25.

Flowers per lateral stem: Average 100.

Inflorescence size:

Width.—6 cm.

Height.—8 cm.

Individual flowers:

Type.—Rotate.

Habit.—Whorled outward.

Diameter.—3 cm.

Length.—1.5 cm

Persistence.—Self-cleaning.

Fragrance.—Lightly earthy.

30 Petals:

Arrangement.—Whorled.

Number.—6.

Shape.—Undulate orbicular shape.

Margin.—Irregular ruffled lobes, undulate.

Tip shape.—Rounded.

Base shape.—Rounded.

Length.—1 cm.

Width.—8 mm.

40 *Texture*.—Upper: Soft, smooth, delicate. Lower: Soft, smooth, delicate.

Color.—When opening: Upper surface: RHS Red-Purple NN74B. Under surface: RHS Red-Purple NN74B. Fully opened: Upper surface: RHS Red-Purple NN74B. Under surface: RHS Red-Purple NN74B. Fading: Upper surface: RHS Red-Purple 61C. Under surface: RHS Red-Purple 61C.

Bud:

Shape.—Obovate.

Length.—5 mm.

Diameter.—5 mm.

Color.—Center: RHS Greyed-Purple N186C. Outside: RHS Greyed-Purple 187B to 187C.

Sepals:

Appearance.—Smooth, glossy.

Arrangement.—Unguiculate.

Shape.—Narrowly triangular.

Tip shape.—Acute.

Base shape.—Obtuse.

Margin.—Entire.

Quantity per flower.—6.

Length.—4 mm.

Width.—3 mm.

Texture.—Upper: Smooth, coriaceous, rugose. Lower: Smooth.

Color.—Upper: Mix of RHS Red-Purple 59A with Red-Purple 58B to 58C. Lower: RHS Green-White 157A.	Color.—RHS Greyed-Orange 163A edged with Greyed-Orange 165A.
Calyx:	Pollen.—Amount: Some. Color: RHS Greyed-Orange 163A.
Shape.—Unguiculate.	5 Pistil:
Length.—5 mm.	Number.—1.
Diameter.—6 mm.	Length.—2 cm.
Peduncle:	Style.—Length: 1.8 cm. Color: RHS Greyed-Purple 184D.
Length.—3 cm.	10 Stigma:
Diameter.—1 mm.	Shape.—Globe.
Texture.—Smooth.	Color.—RHS Black 202A.
Color.—RHS Greyed-Red 182A.	Ovary color.—RHS Yellow 11B.
Strength.—Good.	
Pedicel: None.	15 OTHER CHARACTERISTICS
REPRODUCTIVE ORGANS	
Stamens:	Fruits and seeds: Not observed to date.
Number.—About 29.	Disease/pest resistance: Neither resistance nor susceptibility to normal diseases and pests of <i>Lagerstroemia</i> observed.
Filament length.—1 cm.	Temperature range: Observed to tolerate a temperature range from -28° C. to 35° C. Root hardy to -28C, top of the plant does die back to the ground.
Filament color.—RHS Red-Purple 70D, with White 155B at base.	What is claimed is:
Anthers:	1. A new and distinct cultivar of <i>Lagerstroemia</i> plant named 'SMNLIDS' as herein illustrated and described.
Shape.—Linear.	* * * * *
Length.—1 mm.
